UNITED STATES PATENT OFFICE.

CARLETON B. HUTCHINS, OF DETROIT, MICHIGAN.

HEAT-INSULATING WALL FOR REFRIGERATORS AND CARS.

SPECIFICATION forming part of Letters Patent No. 339,183, dated April 6, 1886.

Application filed September 29, 1885. Serial No. 178,516. (No model.)

To all whom it may concern:

Be it known that I, CARLETON B. HUTCHINS, a citizen of the United States, residing in Detroit, in the county of Wayne and State 5 of Michigan, have invented a new and useful Improvement in Heat-Insulation Walls for Refrigerators and Cars, of which the following is a specification.

This invention relates to means for rendering the walls of refrigerator-chambers, and more especially refrigerator-cars, non-conducting to heat.

My purpose has been to produce a wall which shall be easily and cheaply constructed, 15 not liable to be affected by changes in the atmospheric conditions of heat and moisture, which shall not be liable to become more pervious to heat by reason of the straining to which it may be subjected when used as the 20 wall of a refrigerator-car, which is not liable to rapid decay or change of any kind, and which shall give a better insulation than has ordinarily been obtained. After considerable 25 experiment, I find that these results can be best achieved by the following construction, which I will describe in connection with the accompanying drawing, showing a cross-section of my improved refrigerator-car, promising, however, that the present invention 30 relates only to the means for producing heat-insulation, and not to the internal arrangement of the car.

In making a refrigerator car or chamber according to this invention, I construct the 35 same of double walls—an outer wall, A, and an inner wall, B—leaving an open space between the two. In order that this open space may be left entirely clear and coextensive with the entire wall, I prefer to make the two 40 walls in some manner so that a frame-work may be dispensed with. This may be done in various ways; but the best method which I have thus far devised is the one indicated in the drawing, where the said walls are shown 45 to be made of strips of wood nailed or secured flatwise one upon another, as bricks are laid in a building. The object is to secure a strong self-supporting double-wall structure with a clear space, C, between the two walls, which 50 may be readily filled. This clear space I fill with woolen rags cut into shreds, preferably of sufficient fineness so that they will readily

pack. Such rags may be obtained already shredded of the paper-makers, to whom they are of comparatively small value. Rags having some admixture of cotton may be employed, but not with the best results, because the cotton is more likely to absorb moisture, and thus to partially lose its insulating properties. I am aware that unmanufactured wool 55 has been employed for this purpose; but my filling is better, cheaper, and more durable, packs better, and is less liable to change in bulk after packing.

I am well aware that it has long been customary to construct the walls of refrigerator-chambers with a space to be filled with some packing material, such as sawdust, tan-bark, straw, dry leaves, and like vegetable substances; but these materials are exceedingly 60 liable to absorb moisture readily, to engender fungoid and moldy growths, and to speedily decay, the result being that the chamber is liable to become tainted and to lose its insulation. I am also aware that asbestos has been 65 used; but, although less liable to change than the vegetable substances above named, it is almost equally subject to acquire dampness, and even when dry does not possess the desired non-conducting qualities. I am further 70 fully aware of the fact that various coarser kinds of felt, made sometimes partly of hair and various sorts of paper, sometimes impregnated with antiseptic substances, have been used as a lining for refrigerating-chambers. 75 The objection to all such insulation is that the material is applied in the form of sheets secured to the surface of the wall by cement or nails or otherwise, and where employed in refrigerator-cars, even if a sufficient thickness 80 or number of layers to produce the requisite insulation be used, such structures, by reason of the racking of the car, are liable to open at the joints, if originally made tight, so that air-currents are engendered at some particular 85 points and the insulation materially injured. Moreover, it is very difficult to originally produce a tight wall by means of insulating material applied in sheets. These difficulties are entirely overcome by the use of 90 the cut woolen rags firmly packed in. Such a packing of woolen shreds is pervious to the air in every direction equally, and consequently it is exceedingly difficult, if not im- 95 100

possible, to engender any current in a particular direction.

I am informed that, theoretically, the best non-conductor of heat known is a dead-air space, in which the air shall be perfectly motionless; but as any change in the temperature in the air at one point of such space is sure to cause a current and a consequent transmission of heat by convection, I have 5 concluded that the air-space filled with the pervious unchanging material that I employ is the nearest approach to perfect heat-insulation now known, as it is not liable to absorb moisture, not liable to decay and taints, may 10 be equally and evenly packed, cannot sift out through small apertures, is exceedingly cheap 15

and easily applied, does not require to be secured by cement, perforated with nails, nor impregnated with any antiseptic, adds slightly to the weight of the car, is equally pervious 20 in all directions to the air, and not more pervious at one point or direction than another.

I claim—

The insulating structure for refrigerator-chambers, consisting of an inner and an outer 25 wall and a filling of woolen shreds or small woolen rags, substantially as specified.

CARLETON B. HUTCHINS.

In presence of—

W. M. LILLIBRIDGE,
E. R. HUTCHINS.
